UNITED STATES PATENT OFFICE.

HERBERT W. SELLNER, OF FARIBAULT, MINNESOTA.

AMUSEMENT APPARATUS.

Application filed May 13, 1927. Serial No. 191,058.

This invention relates to amusement apparatus and is an improvement on the invention disclosed in my pending application entitled "Amusement device", S. N. 104,816, filed April 24, 1926. My said original invention comprised an amusement device of the round-about type having a plurality of circumferentially disposed wheeled platforms or trucks moved over an undulating track by means of a large revoluble frame having radially extending arms; said trucks or platforms being tilted on two different axes to impart spinning and oscillatory movement to the cars which were eccentrically pivoted thereon. The spinning or oscillatory movement of the cars upon the several platforms would often continue after the movement of the revoluble frame had stopped thereby endangering the safety of passengers when endeavoring to alight. The frame work and construction of the revoluble frame and track moreover was not such that it would be especially adapted for quick assembling or compact shipping. Moreover, in my original device no means were provided for preventing passengers from stepping or falling off the loading platform between the several radial arms.

An object of my present invention is to provide an improved amusement device or apparatus similar in many respects to my original invention, but having efficient means controllable from without the ride for simultaneously and instantly stopping the oscillatory and spinning movement of the several passenger cars upon their respective platforms or trucks.

A further object is to provide in an amusement device of the class described, an extremely simple but highly efficient knock down frame for supporting the revoluble frame and the undulating track, which is especially adapted for compact transportation and which moreover may be set up or disassembled in a very short time.

A still further object is to provide in an amusement device of the type described, special railings extending between the outer ends of the several radial arms in juxtaposition to the landing platform, said railings being constructed for proper disposal relative to the landing platform at all times during the movement of the trucks over the track without interfering with the undulatory movement of said trucks.

These and other objects of the invention

will be apparent from the following description made in connection with the accompanying drawings, in which like reference characters refer to similar parts throughout the several views, and in which:

Fig. 1 is a plan view of an embodiment of my improved assembled amusement apparatus;

Fig. 2 is a plan view on a large scale of the hub structure for my revoluble frame and the 65 brake actuating mechanism disposed thereon;

Fig. 3 is a vertical section taken on the line 3—3 of Fig. 2;

Fig. 4 is a cross section taken on the line 4—4 of Fig. 3, showing the levers for operating 70 my brake actuating head and the connection of said levers with said head;

Fig. 5 is a vertical section taken through the pivot of one of the passenger cars showing one of the braking mechanisms applied to 75 said car;

Fig. 6 is a cross section taken on the line 6—6 of Fig. 5;

Fig. 7 is a side elevation of one of the levers for controlling the brake actuating 80 head, detached;

Fig. 8 is a fragmentary side elevation of my railing structure supported from a pair of the tilting trucks or platforms; and

Fig. 9 is a section taken on the line 8—8 85 showing a portion of said railing structure in rear elevation.

The embodiment of the invention illustrated, comprises a large supporting frame, designated as an entirety by the letter A, 90 preferably comprising a plurality of radially disposed sections. Each section is made up of upper and lower angle bars 10 and 11 respectively, and upright transverse angle bars 12 secured across the end portions of said 95 horizontal angle bars. It will be seen, in Figs. 2 and 3 that the inner ends of the horizontal angle bars project slightly beyond the adjacent uprights 12 and are disposed in the circumference of a circle. The inner ends of 100 the lower angle bars 11 are detachably secured to a flanged pedestal 14 by means of relatively heavy bolts 15 preferably held in place by means of cotter pins 15^a. An upper flanged collar 16 is secured to the projecting 105 inner ends of upper angle bars 10 by means of suitable bolts 17 passing through flange 16^a of said collar, said bolts being provided with retaining means at their inner ends, such as the cotter pins 18. An upright pivot 110

shaft 19 is supported in pedestal 14 passes through collar 16 and projects a considerable distance above said collar. Collar 16 is preferably rigidly secured to pivot shaft 19 by means of a heavy set screw 20. Collar 16 has a horizontally disposed annular bearing surface at its upper end on which the hub 21 for my revoluble frame is supported. Hub 21 is journaled about shaft 19 and carries an 10 upstanding flange 21^a concentric with said pivot shaft, said flange being provided with a plurality of horizontal and radially disposed bearing ports adapted to receive the heavy pins 22 for connection with the sweeps 15 or arms of the revoluble frame. Retaining collars 23 are rigidly secured to the inner ends of pins 22 and said pins carry at their outer ends spaced ears 22^a to which the inner ends of the sweeps are pivoted on normally 20 horizontal axes. The sweeps or arms each comprise a pair of diverging angle bars 24 having their inner ends disposed flush within pivot ears 21^a and pivotally secured thereto by means of small transverse bolts 25. The 25 outer ends of the several sets of angle bars 24 are spaced some distance apart and are secured to the tiltable platforms or trucks 26. Each of the trucks is mounted on a pair of wheels 27 mounted adjacent the sides of the 30 platforms in tandem arrangement. The axles of wheels 27 extend radially with reference to pivot shaft 19, whereby said wheels will follow the narrow undulating circular track 28. This track is preferably made up 35 in arcuate sections, each of said sections being secured to and supported from the outer ends of a pair of the upper angle bars 10 of the supporting frame. To properly position the annular undulating track it is, of 40 course, necessary to vary the height of the uprights 12 at the outer ends of the frame section. Because of the length of the frame sections the relatively small variance necessary for the undulated track will make little 45 difference in the variance of the disposition of the inner ends of angle bars 10. A concentric undulated landing platform 29 is built around supporting frame A, being undulated symmetrically with track 28. The 50 landing platform is disposed in juxtaposition with the outer ends of truck platforms 26 whereby the passengers may easily mount or alight from the trucks.

A relatively small circular track 30 is carried by each of the platforms 26 on which the circumferentially disposed wheels of an eccentrically pivoted passenger car 31 travel. Each of the passenger cars 31 has a rider's seat at its outer end and has its forward end 60 pivoted to the central part of platform 26 by means of a large vertical pivot post 32. As shown in Fig. 5, the forward pivoted end of each of the passenger cars rigidly carries a depending brake drum 33 concentric with 65 pivot post 32 and disposed between the bot-

tom of passenger car 31 and platform 26. Pivot post 32 receives a great amount of strain and for that reason a heavy boss 34 is provided secured to platform 26 bearing at its upper end against the inner face of 70 drum 33 and a reinforcing block 35 is interposed between the lower end of pivot 32 and the platform.

Internal brake shoes 36 of the expansion type are housed within drum 33 and are pivoted to platform 26 by means of a bolt 37. These brake shoes are shown of semi-annular form having opposing free ends spaced apart. A vertically disposed oval-shaped camming member 38 is interposed between 80 said opposing ends and is carried by the upper end of a short vertical rock shaft 39 journaled in platform 26. Rock shaft 39 carries the lever 40, these levers on the several trucks or platforms being connected to suitable brake actuating mechanism by means of flexible members or cables 41.

A slideable brake actuating head 42 is mounted on pivot shaft 19 and is adapted to move vertically between collar 16 and a set 90 screw collar 43 secured to shaft 19 directly above pedestal 14. Brake head 42 preferably includes a relatively long sleeve portion telescoped about the pivot shaft and a relatively wide annular flange 42^a, said flange carrying adjacent its peripheral edge a plurality of upstanding pins 44 which support a horizontally disposed contact ring 45. Contact ring 45 is preferably of somewhat larger diameter than the hub 21 and is adapted to encircle the lower portion of the hub, as illustrated when actuating head 42 is moved to extreme upward position. A plurality of circumferentially spaced relatively small brake operating levers 46, one for each 100 car, are pivoted on horizontal axes between bifurcated lugs 48 rigidly secured to the periphery of hub 21. Levers 46 have relatively short curved lower ends 46^a adapted to be contacted by ring 45 and have relatively long 110 upstanding ends to which the ends of cables 41 are secured. As shown in Fig. 1, cables 41 extend substantially radially from the hub of the revoluble frame connecting levers 46 to the actuating mechanism with levers 40 115 on the several brake cams.

Brake actuating head 42 is moved vertically on shaft 19 by means of bell crank levers 47, one disposed at each side of collar 43 and horizontally pivoted thereto. Bell crank levers 120 47 have relatively long upstanding ends to which the operating cable 48 is secured and relatively short horizontal ends 47^a connected to the sides of actuating head 42 by means of links or pitmen 49. Operating cable 48 is 125 preferably extended beneath the revoluble frame to a point adjacent the motor X for the operator's convenient manipulation.

The revoluble frame may be driven in any suitable manner, such as by means of the end- 130

less cable 50, frictionally engaging members depending from the several trucks.

I provide special railing structure, see Figs. 1, 8 and 9, extending between the trucks or platforms in close proximity to the inner periphery of the landing platform to prevent accidents to persons stepping onto the trucks. This structure preferably comprises an arcuate rail 51 extending between two of the adjacent platforms 26 pivoted at one end by means of bolt 51^a to a normally upright post 52, which post is preferably pivoted on a horizontal axis between upstanding ears 53 secured to the upper side of the platform. The lower end of post 52 is preferably formed into a square ended loop portion which is disposed between ears 53. The other end of rail 51 is secured to a second upstanding post 52^a, said post having the lower loop portion pivoted between a pair of ears 53. Post 52^a is rigidly connected with rail 51 by means of a diagonal bracing member 54.

Operation.

In operation the arms or sweeps are revolved about shaft 19, trucks 26 passing over the annular undulating track. The undulations of the track cause the platforms to each tilt on two different axes. Each truck having its wheels arranged in tandem, tilts endwise on the axis of one of the pins 22 and also tilts sidewise on the axis of one of the bolts 25, which hinges its arm or sweep to pin 22. The various tiltings to which the cars are subjected depend, of course, on the undulations of the track. The effect from the tilting on two axes causes the passenger cars 31 to swerve suddenly about vertical pivots 32, sometimes spinning completely through one or more revolutions and sometimes oscillating from one side to another. In the event that the movement of the cars becomes too violent, for one or more of the passengers, the operator can readily check the same or completely stop the movement of the cars by pulling cable 48. This swings the levers 47, sliding brake actuating head upwardly and thereby causing contact ring 45 to actuate the brake lever 46. Levers 46 are connected with cam levers 40 which set the brake shoes 36 against their housings 33. When a ride is terminated several of the trucks 26 will be supported at least partially over the undulations of the track and the passenger cars will continue to swing or oscillate for some time unless checked. With my improved device the operator actuates the brake mechanism as the movement of the revoluble frame is checked whereby the cars will all be held rigid on the platform of the trucks permitting the passengers to alight without risk of injury.

It will be apparent that my braking mechanism previously described may be operated from without the ride at any time to simulta-

neously stop the movement of all cars on their trucks, whether the revoluble frame is moved fast or slow.

In providing railing structure between the platforms in my amusement apparatus two factors had to be carefully considered. First, during the operation of the ride it seldom occurs that two adjacent trucks are disposed on the undulating track at the same level. Consequently, the railing structure must swing to conform to the difference in levels and still must not interfere with the tilting of the platforms. Secondly, the protective rail must be kept at all times in substantially parallel position with and above the landing platform and in juxtaposition thereto. By hinging the upright posts 52 and 52^a on horizontal axes to the platforms and by rigidly connecting one end of each arcuate rail with one of the posts and by pivoting the other end of said rail to the post on the adjacent truck all requisites are met.

To disassemble supporting frame and revoluble frame of my device it is only necessary to remove the cotter pins from the pins 15 and 17 thereby detaching the radial supporting sections from the hub structure. The arcuate track portions 28 may then be removed and the sweeps or arms removed from the hub 21. The supporting frame sections may be stacked together for shipment, requiring little space while the arcuate track sections may be secured together for shipping and are sufficiently short for easy transportation in a motor truck or box car.

It will, of course, be understood that various changes may be made in the form, details, arrangement and proportions of the parts without departing from the scope of the invention.

What is claimed is:

1. In amusement apparatus a revoluble frame, a plurality of passenger cars pivotally mounted on said frame and adapted to oscillate or spin thereon as said frame revolves, brake mechanism interposed between each passenger car and said frame for holding said cars rigid with said frame, and means for simultaneously actuating said several brake mechanisms.

2. In amusement apparatus a fixed pivot member, a revoluble frame adapted to revolve on the axis of said pivot member, a plurality of passenger cars pivotally mounted on said frame and adapted to oscillate or spin thereon as said frame revolves, brake mechanism interposed between each of said cars and said frame, and brake actuating mechanism mounted on said pivot member and connected with said several brake mechanisms to simultaneously actuate the same.

3. In amusement apparatus a fixed pivot member, a revoluble frame having a hub adapted to revolve on said pivot member a plurality of passenger cars pivotally mounted

on said frame and adapted to oscillate or spin thereon as said frame revolves, brake mechanism interposed between each of said cars and said frame, actuating mechanism associated with said hub and said pivot member for simultaneously controlling said several brake mechanisms.

4. In amusement apparatus a fixed pivot member, a revoluble frame having a hub adapted to revolve on said pivot member a plurality of passenger cars pivotally mounted on said frame and adapted to oscillate or spin thereon as said frame revolves, brake mechanism interposed between each of said cars and said frame, a plurality of levers mounted on said hub each connected with one of said brake mechanisms, and an actuating head mounted on said pivot and adapted to simultaneously engage all of said levers.

5. In amusement apparatus a circular undulating track, a plurality of radially disposed arms mounted for revolution about a vertical pivot, trucks mounted beneath the outer ends of said arms adapted to pass over said track, passenger cars mounted on the outer ends of said arms, and a plurality of arcuate railings concentric with said track and each extending beneath the outer ends of a pair of said arms and hinged at its ends to said arms.

6. In amusement apparatus a circular undulating track, a plurality of arms disposed radially to said track mounted for revolution about a vertical pivot concentric with said track, said arms carrying trucks adjacent their outer ends adapted to pass over said track, passenger cars mounted on the outer ends of said arms and a plurality of railing structures each extending between the outer ends of a pair of said arms, each of said structures comprising an arcuate rail disposed concentric with said track, an upright post hinged to one end of said railing and to one of said arms and a second upright post rigidly connected to one end of said rail and hinged to one of said arms.

7. In amusement apparatus a circular undulating track, a plurality of arms disposed radially to said track, a vertical pivot member disposed concentric with said track, a

hub having connection with the inner ends of said arms, said arms carrying trucks adjacent their outer ends adapted to pass over said track, passenger cars eccentrically pivoted to the outer ends of said arms, brake mechanism interposed between each of said passenger cars and its arm, a plurality of horizontally pivoted levers mounted on said hub and connected with said several brake mechanisms, the lower ends of said levers extending below said hub, an actuating head slidably mounted on said pivot member adapted to engage the lower ends of said levers and means for moving said actuating head controllable from without said track.

8. In amusement apparatus, a substantially vertical pivot member having a flanged base and including a flanged member disposed at some distance above said base and substantially vertically aligned therewith, a plurality of radially disposed vertical frame sections, each comprising an upper and lower rail, said upper rails being readily connectable with said upper flange and said lower rails being readily connectable with said base, said lower rails being adapted to rest on a supporting surface, a plurality of arcuate track sections concentric with said pivot and each traversing the outer ends of two of said frame sections and being readily connectable therewith, a revoluble frame having a hub mounted on said pivot member, a plurality of radial arms or sweeps readily connectable with said hub and a plurality of trucks connected with the outer ends of said arms and adapted to travel over said track.

9. In amusement apparatus, a central pivot member, a framework mounted for revolution on the axis of said pivot member, a passenger car mounted on said framework for independent pivotal movement thereon, brake mechanism interposed between said car and the portion of said framework on which said car is mounted, brake actuating mechanism mounted on said pivot member, and connections between said brake actuating mechanism and said brake mechanism.

In testimony whereof I affix my signature.

HERBERT W. SELLNER.
